UNITED STATES PATENT OFFICE

2,602,163

LENGTHENABLE GARMENT

Bernice E. Davenport, Portland, Oreg.

Application November 19, 1948, Serial No. 60,879

2 Claims. (Cl. 2—75)

1

My invention pertains to children's clothing, and relates particularly to the novel construction of and method of making a child's garment whereby the latter may be lengthened to accommodate normal growth of the child without producing permanent markings on the cloth or otherwise evidencing the fact that the garment has been altered.

During the early years when a child's growth is most rapid, it is a common practice among mothers to purchase for their children dresses, slips and other skirt-type garments in sizes substantially longer than immediate requirements dictate. The garment is then shortened by forming circumferential hems therein which are secured in place with stitching. These hems are arranged symmetrically and are designed to ornament the garment in the best possible manner. As the child grows in stature, one or more of these hems or folds are eliminated by removing the stitching whereby the garment is made longer. This method is not completely satisfactory, however, for as each fold is eliminated the holes formed in the cloth by the needle and thread previously employed in the stitching do not disappear. The garment is thus marked permanently, giving visible evidence that it has been lengthened.

It is a principal object of my invention, therefore, to provide a method of making a child's skirt-type garment whereby alterations in length may be accommodated without permanently disfiguring the cloth or otherwise giving evidence of such alteration.

Another important object is the provision of a child's skirt-type garment which may be altered in length without disfiguring the cloth or otherwise giving visible evidence of such alteration.

A further object of my invention is to provide a child's garment in which spaced circumferential rows of hemstitching are utilized both as ornamentation and as securing means for hems or folds formed therebetween, whereby said garment may be altered in length without permanently disfiguring the cloth.

These and other objects and advantages of my invention will appear from the following detailed description taken in connection with the accompanying drawing, in which:

Fig. 1 is a fragmentary plan view of a child's garment embodying the features of my invention, the left hand portion showing a series of circumferential rows of hemstitching, and the right hand portion showing the manner in which

adjacent rows of hemstitching are utilized in forming folds for shortening the length of the garment; and

Fig. 2 is an enlarged fragmentary sectional view taken along the line 2—2 in Fig. 1 and showing in detail the manner in which the fold is secured in place.

The garment illustrated in the drawing for purposes of explaining the novel features of my invention represents a child's dress, although it is to be understood that my invention is applicable to slips and other garments having similar features of general design. The dress shown comprises a full length body portion 1 which includes both bodice and skirt section. The usual neck opening 2 and armholes 3 are provided, as well as the ruffled hem 4, the latter being secured to the lower edge of the skirt by means of stitching 5.

20 A plurality of rows 6, 7, 8 and 9 of hemstitching are formed circumferentially about the lower portion of the skirt. Hemstitching, as is well known, is produced by removing or displacing a few parallel strands of thread from a cloth and then tying the cross threads into bundles. This produces a series of holes 10 separated by the small clusters or bundles of tied threads. This is used extensively in forming ornamental borders and other designs in a large variety of cloth articles. In the present invention the rows are spaced from each other a desired distance along the longitudinal dimension of the dress. The spacing between rows may be uniform, as shown, or they may be irregular. It is to be noted, referring particularly to Fig. 2 of the drawing, that the distance between cooperating pairs of hemstitched rows is equal to one-half of the width of the fold 11 to be formed as is explained more fully hereinafter.

40 In shortening the overall length of the dress, the material lying between adjacent pairs of hemstitched rows is gathered outwardly and folded together in back-to-back relationship. The adjacent rows of hemstitching are thus brought into registration with the holes 10 arranged therein in cooperative alignment. A thread 12 is then stitched longitudinally along the hemstitching, and because of the holes 10 and the clusters or bundles of thread lying between said holes, the stitching thereafter removed is not noticeable.

50 That is, the thread bundles do not evidence the piercing produced by the stitched thread as would a flat woven fabric.

In the illustration shown in the drawing it is 55 to be observed that the four rows of hemstitching

provide for the formation of two hems or folds. Thus, rows 6 and 7 are drawn together as shown in Fig. 2, and secured by thread 12 to produce fold 11. Rows 8 and 9 may be drawn together and secured in a similar manner to form the second fold, if desired. Obviously, if provision for more folds is desired, a greater number of ornamental hemstitch rows may be formed in the garment. Since the four rows illustrated are spaced apart equal distances, the two folds will likewise be spaced apart a distance substantially equal to the width of the fold. If it is desired to have the folds overlap or to be spaced closer together than shown, the spacing between rows 1 and 8 may be adjusted to produce this result. In any event, it is to be noted that symmetry of ornamental design is maintained regardless of the number of hemstitch rows and of the location of the folds. Moreover, the folds may be constructed so as to simulate ruffles and thereby enhance the appearance of the garment.

When it is desired to lengthen the dress to accommodate growth of the wearer, one or more folds are eliminated by removing the thread 12 from the cooperating rows of hemstitching. Since the thread has been drawn through the bundles of thread between holes 10, its removal merely brings the hemstitching into view. Thus, the dress is lengthened without causing permanent marking of the cloth which would give visible evidence that the garment had been altered.

Although I have described the features of my invention as applied to the skirt-type garments of small, growing children, it is to be understood that the invention is adaptable with equal success to the garments of adults. Ordinarily, the garments of adults are discarded before changes in length become necessary, and therefore the features embodying my invention are applied principally to the clothes of the rapidly growing child.

I claim:

1. A garment comprising a cloth skirt, at least one cooperating pair of spaced rows of ornamental hemstitching formed circumferentially about said skirt, said cooperating rows being in alignment and in overlying complementary registration one with another, a thread stitched longitudinally through said registering rows and se-

curing the same together with a fold in the cloth lying therebetween, whereby to produce shortening of the length of said garment, said stitched thread being removable from said rows for eliminating said fold, whereby lengthening of said garment is effected without giving visible evidence without giving visible evidence of the alteration.

2. A selectively lengthenable cloth garment, comprising a skirt having a plurality of parallel spaced rows of ornamental hemstitching formed circumferentially thereabout, each such row including a series of holes separated by small bundles of tied threads, at least one pair of said parallel rows being in direct overlying abutment one with another, the material between said pair of rows being folded on a circumferential line intermediate said pair to register the same in abutment, and a thread means stitched longitudinally down said abutting and registering rows of hemstitching and through abutting ones of said small bundles of tied threads temporarily to interlace and fix said rows in abutment with said folded material pendent therefrom, said garment being lengthenable with no visible evidence of alteration by removing said thread means from said bundles of tied threads and opening said folded space.
